UNITED STATES PATENT OFFICE.

ARTHUR W. CAPS, OF TOPEKA, KANSAS, ASSIGNOR TO THE PIERSEN MANUFACTURING COMPANY, OF TOPEKA, KANSAS, A CORPORATION OF KANSAS.

ENGINE RADIATOR.

1,417,027.

Specification of Letters Patent. Patented May 23, 1922.

Application filed July 22, 1920. Serial No. 398,205.

To all whom it may concern:

Be it known that I, ARTHUR W. CAPS, a citizen of the United States, residing at Topeka, in the county of Shawnee and State 5 of Kansas, have invented certain new and useful Improvements in Engine Radiators; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to engine cooling systems in which a cooling fluid is circulated through a water jacket surrounding the power cylinder or other part of the engine to be cooled.

20 The generic principle of a water cooling system is well known as involving a water jacket, a source of heat radiation or heat dissipation, and an impeller, usually a pump, for inducing circulation of the fluid 25 through the system, including the radiator, the cooling jacket and the connections between the same.

The present invention contemplates the provision of means whereby the fly wheel of 30 the engine may be utilized as the heat dissipating element and in order to induce circulation through the fly wheel and through the water jacket, I have provided an impeller in the circulating system. The impeller has movement in response to movement of the fly wheel and one of the features 35 of my invention is the novel, convenient and easily accessible construction of impeller so associated with the fly wheel that access may 40 be had thereto for the purpose of inspection or repairs, the organization being such that ease of assemblage as well as simplicity of manufacture is provided for.

In the drawings, 45 Fig. I is a view partly in elevation and partly in section through an engine and cooling system constructed in accordance with my invention.

Fig. II is an end view of the impeller 50 casing with the end cover removed, showing the impeller fans therein, and

Fig. III is a disassociated view of part of 55 the fly wheel radiator, part of the fly wheel head and part of the impeller casing.

The invention is shown as applied to a

vertical type of stationary, reciprocating gas engine which may be of any preferred construction and which is provided with a water jacket 1 about the power generating cylinder or cylinders 2 above the crank case 3 supported upon the base 4.

The usual crank shaft 5 carries a rotating radiator which also constitutes the fly wheel. The radiator is shown as provided with a split hub 6 keyed to the shaft 5 as at 7 and 65 further fastened by the bolt 8.

The radial spokes 9 on the hub 6 support a rim 10 consisting of a peripheral flange having a circular series of lateral slots 11. The flange 10 provides a recess or pocket 70 about the hub 6, within which is received a heat dissipating radiator consisting of ring laminations 12 spaced apart and supporting U-shaped tubes 13 passing through them, and through which the cooling water may 75 circulate to permit air entering the recessed fly wheel to contact with the tubes and the laminations and carry off the heat through the slots 11, provided in the rim 10 on the spokes 9. The edges of the slots in the rim 80 are so disposed that air stream lines will be directed with considerable force beyond the perimeter of the fly wheel to induce an efficient circulation through the radiator. The radiator element may be secured to the edge 85 14 of the flange 10 by the supporting plate 15, which is a ring-shaped member of greater diameter than the diameter of the laminations and which has its inner edge 90 projecting inwardly beyond the inner edges of the laminations 12, as clearly indicated in Figs. I and III.

There is also a head 16 for closing one side of the fly wheel and said head is provided with an off-set flange 17 of substantially 95 the same diameter as that of the ring 15 and of the rim 10 so that the flange may clamp the ring 15 between it and the edge 14, there being preferably a packing 18 provided between the flange 17 and ring 15, as shown 100 in Fig. I.

The fastening devices for effecting the securing of the parts together are shown as bolts 19, (Fig. I) so that the radiator may 105 be held in place.

The head 16 is provided on its inner face with circumferential beads or flanges 20 and 21 adapted to bear against the plate 15 to provide circulating passages 22 and 23. The bead or flange 21 is adapted to be clamped 110

to the inner portion of the ring 15 by a packed joint consisting of the packing 24 and the clamping ring 25, there being bolts 26 provided which pass through the clamping ring 25, the plate 15, the packing 24 and enter the threaded opening in the bead or flange 21.

The hub of the head 16 consists of a sleeve 27 adapted to communicate with the passage 22 through the medium of the radiator port 28. Concentric with the sleeve 27 and of considerably smaller diameter is a tubular member or port 29 integral with the head and communicating with the passage 23 through the medium of a radial port 30 shown as diametrically opposite the port 28. The sleeve portion 27 of the hub is provided with external threads 31 and with an internal shoulder 32, the shoulder being adapted 15 to rest upon the sleeve bearing 33 of the impeller housing or casing 34, concentric with the fly wheel and head. The bearing or impeller member 33 extends into the sleeve 27 and a joint is provided by the gland or packing 35, clearly shown in Fig. I.

The end of the tubular member 29 is provided with a shoulder 36 and a constricted, threaded neck or end 37. When the impeller casing is connected to the sleeve 27, the inner edge of one wall 38 will rest upon the tubular member 29, permitting the restricted portion 37 to extend into the casing to receive the hub 39 of the impeller comprising the hub, a disk 40 secured to the hub, and blades 40' secured to and extending at right angles to the disk. The impeller hub 39 may rest against the shoulder 36 and be secured fast to the tubular member or shaft 29 through the medium of a fastening device, shown as 45 a nut 41. The impeller housing may be closed by a cover member 42 secured to the housing by fastening devices 43, as will be apparent by reference to Fig. I.

There is a radial port 44 carried by the casing 34 which communicates directly with the chamber 45 formed by the members 29 and 33 and this port is adapted to communicate with the outlet 46 of the water jacket 1 through the medium of a conduit or pipe 50, the outlet port 48 for the casing 34 being adapted to communicate with the inlet port 49 of the water jacket 1 through the medium of a pipe or conduit 50.

When the parts are assembled and the 55 crank shaft 5 rotates, the fluid will pass from the top of the water jacket through port 44 into the chamber formed by 27, 33 and 29, and through the port 28 into the chamber or recess 22. There the water will 60 pass through the U-tubes 33 into the chamber or recess 23, through port 30 into the passage formed by the tubular member 29 and into the center of the impeller casing where the impeller 40, being mounted axially 65 and rigidly with the fly wheel, will act upon

the fluid in the casing 34 to force it through pipe 50 and through the inlet port of the water jacket, further inducing circulation.

Therefore, it will be seen that as the engine 70 operates, the fly wheel and radiator will rotate, causing a continuous circulation of the cooling fluid within the fly wheel and the impeller in the casing 34.

When it is desired to inspect the interior 75 of the fly wheel radiator or the impeller for any purpose, it will be only necessary to take off the plate 42, loosen the packing gland 35 whereupon the impeller casing may be separated from the fly wheel upon removal of the nut 41.

It will also be apparent that the mechanism is such that it can be readily assembled 80 without complicated tools or especially skilled labor.

The manner of circulating the air will be 85 apparent by reference to the drawings, from which it will be seen that the air will enter between the spokes 9 and pass between the laminations, over the tubes 13, and out through the slots 11, dissipating the heat absorbed by the fluid as it passes through the 90 water jacket.

Of course, in actual practice, it is essential 95 that some means be provided for anchoring the impeller casing, the particular means being unimportant. However, for convenience I have shown the impeller casing as anchored to the base plate 5 by a standard or rod 52, which engages the perforate lugs 53 on the impeller casing 34.

What I claim and desire to secure by Letters-Patent is:

1. The combination of a rotating radiator, an impeller casing communicating with the radiator, a ported impeller shaft within the impeller casing and in ported communication with the rotating radiator, and an impeller thereon, said impeller casing and impeller being distant from but concentric with the rotating radiator.

2. The combination of a fly wheel with a radiator carried by the fly wheel having ports through which a fluid may circulate, an impeller casing communicating with the ports in the radiator and concentric therewith, a shaft integral with the radiator and extending into the impeller casing.

3. A fly wheel having a peripherally slotted rim, a radiator within the fly wheel comprising laminations and transverse, U-shaped tubes passing through the laminations, a head on the fly wheel having chambers communicating with the opposite ends of the U-shaped tubes, an impeller casing communicating with the ports in the head, said impeller casing being remote from but concentric with the head, means for removably connecting the impeller casing and the head together, an impeller within the casing receiving motion from the head.

4. A rotating radiator frame having a peripheral flange, a radiator comprising a plate of substantially the same diameter as the frame, radiator tubes carried by said plate, a head, means for clamping the radiator plate between the flange and the head, said head being provided with inlet and outlet ports communicating with opposite ends of the radiator tubes, an impeller casing distant from but concentric with the head, a concentric impeller within the casing and carried by a part of the head whereby when the head rotates, motion will be imparted to the impeller.
5. A rotating radiator frame having a peripheral flange, a radiator element carried by the frame, said radiator element comprising a plate substantially equal in diameter to the diameter of the frame, radiator tubes carried by the plate, a head having peripheral grooves providing water chambers, radial ports in the head communicating with
- the respective water chambers, means for clamping the plate between the head and the flange of the frame, a hollow hub on said head having concentric ports communicating with the first named ports of the head, an impeller casing communicating with the last named ports, an impeller in the casing.
6. A rotary radiator having tubes, a head having a water chamber communicating with the respective ends of said tubes, a hollow hub on said head communicating with one of the chambers, a concentric shaft within the hub communicating with the other chamber, the shaft extending beyond the end of the hub, an impeller casing having a sleeve engaging the hub, a packing gland constituting a water-tight connection between the hub and the sleeve, an impeller on the end of the hollow shaft.

In testimony whereof I affix my signature.

ARTHUR W. CAPS.
